UNITED STATES PATENT OFFICE.

CLAUDE E. BOWERS, OF LOS ANGELES, CALIFORNIA.

DEVICE FOR CONNECTING THE ABUTTING ENDS OF CONCRETE SLABS.

Application filed October 11, 1926. Serial No. 140,739.

This invention relates to a device for connecting the abutting ends of concrete slabs of roadways, which will serve to compensate for the contraction and expansion thereof, as well as to hold the abutting slabs or blocks in alinement, thereby assuring an even surface at the joints.

A main object of the invention is to provide a device which will effectually prevent a vertical or lateral shifting movement of adjacent concrete slabs of a roadway, but will readily permit of a longitudinal movement of the connected slabs.

The above and other objects of my invention will be more fully disclosed in the following specifications, reference being had to the accompanying drawings forming a part thereof, in which:

Fig. 1 is a partial plan view of a concrete roadway with the connecting devices in position.

Fig. 2 is a side elevation of the contractible metal sleeve.

Fig. 3 is an enlarged cross section of the sleeve showing the overlap.

Fig. 4 is a longitudinal section through the sleeve.

Fig. 5 is an enlarged longitudinal section through the concrete roadway taken on line 30 5-5 of Fig. 1.

Fig. 6 is an enlarged longitudinal section through the metal sleeve at its capped end.

Fig. 7 is a detail section through the contractible metal sleeve before contraction.

Fig. 8 is a similar view showing the sleeve contracted into tight engagement with the sleeve engaging rod.

In an embodiment of the present invention the joints are adapted to be formed 40 transversely across the concrete roadway at suitable intervals as shown in Fig. 1 of the drawings, and are constructed in the following manner.

When slab 5 of the roadway 6 has been 45 poured a number of round steel bars or dowels 7 approximately three-fourths (3/4) of an inch in diameter and about twenty-four (24) inches long are inserted in the edge 8 of the slab midway between the top and the bottom surfaces, about half their lengths 50 projecting beyond the edge as clearly shown in the various views of the drawings.

The exposed ends of these rods are then 55 greased or oiled to prevent corrosion or sticking, and the contractible metal tubes 9 are then applied to the exposed ends.

Tubes 9 that form sockets for the projecting ends of the embedded rods constitute one of the important features of the invention and are preferably formed from sheet steel 60 of No. 28 gage about twelve and three-quarters (12 3/4) inches, their longitudinally extending edges 10, 11 overlapping each other about one half an inch in order to permit of a diametrical contraction of the sleeves when 65 pressure is applied thereto, the pressure being exerted thereagainst by the mass of concrete when the same is poured therearound in the formation of the adjacent slab, see Figs. 2, 7, and 8. One end of the tube or 70 sleeve is provided with a die formed metal cap 12, and its opposite end is provided with a metal ring 13, the cap and ring maintaining the tube in its initial shape, the cap also serving to prevent an entrance of wet concrete to the interior of the tube or sleeve during the concrete pouring operation. As the cap 12, and ring 13 are liable to become accidentally detached during handling a small drop of solder 14 may be applied to 75 each to temporarily hold them in position, as shown in Fig. 2.

In order to provide sufficient space within the sleeves to accommodate the movement rods with respect to the sleeves when an expansion of the slabs occur, stops 15 are 80 formed by indenting the surface of the sleeves a distance from the capped end about equal to the normal width of the joints 16, the ends of the rods on an expansion of the 85 slabs forcing the stops outwardly and permitting their passage into the space beyond them.

As initially formed the diameter of the tubes 9 are slightly larger than the diameters of the rods of dowels 7 in order that they may be readily inserted thereon, the pressure of the wet concrete being sufficient to contract the sleeves transversely into a tight "glove fit" with the rods or dowels 95 after the completion of the concrete pouring operation. As the tubes are formed of thin gage metal it will be apparent that when they become disintegrated by corrosion that the sockets formed in the concrete by the tubes will only be slightly larger than the diameter of the rods, and as a result there will be little if any of vertical or lateral movement of the slabs.

After the slabs have been poured and set, 110 the joints between the same are filled with a bituminous mastic or other elastic material

17 in order to prevent leakage of fluid between or under the slabs.

By the above recited construction it will be perfectly obvious that the metal rods or 5 dowels 7 will effectually prevent the slabs or blocks from shifting with respect to one another in either a vertical or lateral direction, thus assuring an even surface and straight edges to the roadway, and that the 10 slabs may expand and contract freely in a longitudinal direction by reason of the rods and sockets. Further as the devices are formed of comparatively inexpensive materials it will be apparent that their cost will 15 be adequately compensated by the benefits derived.

What I claim is:

1. In a device for connecting the slab units of a concrete roadway, a plurality of 20 rods adapted for embedment in an edge of one of the concrete slab units, a portion of the rods extending beyond the edge, and a contractible metal sleeve for each of said rods, said sleeves being embedded in the 25 abutting edge of the adjacent concrete unit.
2. In a device for connecting the slab units of a concrete roadway, a plurality of metal rods adapted for embedment in an edge of one of the concrete slab units, a 30 portion of the rods projecting beyond the edge, and diametrically contractible metal sleeves disposed upon the free ends of the projecting rods, said sleeves adapted for embedment in the abutting edge of the adjacent concrete slab unit.
3. The combination with a pair of abutting concrete road slab units, a plurality of

metal rods partially embedded in an edge of one of the slab units, and a transversely contractible metal sleeve mounted on each 40 of said metal rods, the said sleeves being embedded in the abutting edge of the adjacent slab unit.

4. A device for preventing vertical and lateral movement of concrete road slab units, 45 comprising a plurality of metal rods adapted for partial embedment in an edge of one of said units, and a longitudinally split sleeve mounted on the free end of each metal rod, the concrete of the abutting edge of the 50 adjacent unit surrounding the sleeve and compressing the same into a tight sliding engagement with the metal rods.

5. A device of the class described comprising a plurality of metal rods, a longitudinally split metal sleeve for each of said rods, 55 the rods and sleeves adapted to be embedded in the abutting edges of concrete road slab units, whereby to prevent vertical and lateral movement of the slabs when the same 60 contract or expand.

6. A device of the class described comprising a metal dowel adapted for partial embedment in the edge of a concrete slab unit, and a longitudinally split metal socket 65 member mounted on the dowel, one end of said member having a removable cap, said socket member adapted for embedment in the abutting edge of the adjacent concrete slab unit.

In witness that I claim the foregoing I have hereunto subscribed my name this 2nd day of October, 1926.

CLAUDE E. BOWERS.
